Primary Examiner — Maria J. Edwards*Assistant Examiner* — Dina Michelle Hoeynck(74) *Attorney, Agent, or Firm* — JCIP Global Inc.(57) **CLAIM**

The ornamental design for a gimbal camera, as shown and described.

DESCRIPTION

FIG. 1 is a perspective view of a gimbal camera showing our new design;

FIG. 2 is a front view thereof;

FIG. 3 is a rear view thereof;

FIG. 4 is a left view thereof;

FIG. 5 is a right view thereof;

FIG. 6 is a top view thereof; and,

FIG. 7 is a bottom view thereof.

The broken lines shown in FIGS. 1–5 and 7 represent the bounds of the design. The broken lines and the lighter gray shaded areas of the gimbal camera encircled by the broken lines in FIGS. 1–5 and 7 form no part of the claimed design.
